EARTH ANCHOR

Filed April 18, 1928

INVENTOR.
Chester R. Pieper

BY Allen & Allen

ATTORNEY.

UNITED STATES PATENT OFFICE

CHESTER R. PEEPER, OF LA CROSSE, WISCONSIN

EARTH ANCHOR

Application filed April 18, 1928. Serial No. 271,046.

My invention pertains to earth anchors of the type which comprises blades hingedly mounted in connection with a shaft and adapted to be held in unexpanded position while the anchor is lowered through a prepared hole. Afterwards the blades are caused to expand and enter the earth, giving the anchor such a large bearing surface that it cannot thereafter be removed from the earth. My invention is further specifically applicable to that type of earth anchor in which there is no screw action or rotary motion necessary to expand the blades, but in which the blades are expanded by the action of a tamping tool. Hitherto such anchors have been made with a single pair of cooperating blades. An example of such an earth anchor is shown in my Patent No. 1,123,368, issued January 5, 1915. Where two cooperating blades are provided, the width of the blades is necessarily limited by the width of the original hole in which the anchor is to be used, and the bearing surface of the anchor in the earth is correspondingly limited. The bearing surface may be somewhat increased by lengthening the blades, but this also has its limitations, since the blades cannot be lengthened beyond a certain point without necessitating a redesign of the general structure.

Hitherto, so far as I am aware, there have never been provided anchors of this type having more than two blades. It is an object of my invention to provide such an anchor. It will be clear that several blades, even though their width be necessarily limited by the permissible over all measurements of the device, will nevertheless have much more bearing surface than an anchor with only two blades.

It is a further object of my invention to provide a simple, inexpensive and efficient mounting for the blades which will serve to expand all of them at once uniformly under impacts of the tamping tool.

It is still a further object of my invention to provide a trunnion housing for mounting the blades which will permit quick and easy

assembling of the earth anchor and which will do away with the necessity of mounting the blades upon bolts, rivets, and the like, as bearings.

It is still a further object of my invention to provide means whereby the blades may be held in unexpanded position while the anchor is being inserted in a hole prepared for that purpose, and means for releasing the blades as soon as the trunnion housing has been hit by the tamping tool, so that the further swing of the blades on their trunnions during expansion of the anchor will be free from frictional resistance.

These and other objects to which reference will be made in the ensuing disclosure I accomplish by that certain combination and arrangement of parts of which I have illustrated a preferred embodiment.

In the drawings:—

Figure 1 shows a top plan view of one of my anchors in expanded position.

Figure 2 is a sectional elevation of the trunnion housing showing two blades mounted therein on their trunnions and the anchor shaft passing through the housing.

Figure 3 is a perspective view of one of my blades.

Figure 4 is a side elevation of an expanded anchor.

Figure 5 is a side elevation of my trunnion housing showing the opening to accommodate the neck of one of my blades and showing the trunnion bearings in dotted lines.

Figure 6 is a view of the unexpanded anchor as it is prepared to be lowered into the hole.

While I have shown in these views an anchor having four blades, it will be understood that I do not limit myself to the number of blades in my anchor but may provide more or less, according to the purpose for which the anchor is to be used, the strain it must bear, the character of the soil, etc. The anchor broadly consists of a shaft 1, a bottom plate 2 to the center of which the shaft is fastened in any suitable manner, as by means of the nut 3 on the threaded end thereof. I have shown also a trunnion housing 4 in which the blades 5 are pivotally mounted.

This trunnion housing may be of various shapes, and the shape and size of it will vary, of course, with the size of the anchor and the number of blades. I have shown a rounded 5 trunnion housing in which four of the blades are mounted.

Reference to Figure 3 will show that each blade comprises a flat spade-like portion 6, a neck portion 7, and a trunnion portion 8. 10 The axis of the trunnion portion extends at right angles to the neck portion, and beyond it at either side, so that the trunnion may be used as a means of mounting the blade pivotally in the housing. Each blade has a latch 15 or stop portion 9 for a purpose which will be hereinafter described. It is clearly shown, however, in Figure 3 and the other views showing the trunnion in plan or section, that the trunnion 8, instead of being perfectly 20 cylindrical, is made slightly oval or elliptical in cross section so that it is broader in one transverse direction than in the other.

Reference now to Figure 2 will show my trunnion housing in section. It comprises a body with a top which I have indicated as 10. 25 Below this top there are trunnion sockets 11 in which the trunnions may rotate. The trunnion housing has a bottom portion 12 completing the trunnion sockets but it will be 30 noticed in Figure 2 that a portion has been cut away from the trunnion socket bottoms and sides to accommodate the necks of my blades so that these blades may swing through an angle of 90 degrees from the vertical to the 35 horizontal. These portions I shall hereafter refer to as neck openings, and I have indicated them in Figure 5 by the numeral 13. In my trunnion housing there will be a trunnion socket for each of the blades; and reference to 40 Figure 1, in which the trunnion sockets are indicated in dotted lines in plan for a four-blade anchor, will indicate somewhat more clearly their general disposition. It will also best be understood from this view that 45 through the center of the trunnion housing is an opening 14 for the shaft 1 and that each of the trunnion sockets are open on the side toward the shaft. It will be understood that this opening is of such a size as to permit the 50 trunnion housing to slide freely on the shaft 1, and that the width of the trunnion sockets will be such that the trunnions themselves will not bind against the shaft.

It will now be clear why I make my trunnions of elliptical rather than truly cylindrical shape. When the blades are in the vertical position the elliptical trunnions bind in the trunnion sockets since the major axis of the elliptical cross section of the trunnions is 55 made equal to the depth of the trunnion sockets. The trunnion sockets are, however, wider than they are deep. In the sense that the distance between the open end of the socket (which is closed by the shaft 1) and the 60 curved inner end of the trunnion socket is

greater than the distance between the top and the bottom of the socket. Thus, as soon as the blades 5 have been started from the vertical position indicated by the solid lines in Figure 2 toward the horizontal position indicated 70 by the dotted lines, the binding of the trunnion against the trunnion socket will be released and the blade will then swing freely. The purpose of this binding is to hold the blades in the unexpanded position shown in 75 Figure 6 while the anchor is being lowered into a hole prepared for it. As soon, however, as the tamping tool has been applied to the body of the housing and the blades started from their vertical position, the frictional binding of the trunnions and the sockets, as has been said, will be released, and the blades will expand freely into the earth under the impacts of the tamping tool.

The latch or stop 9 is designed to pass over 80 the edge of the bottom or stop plate 2 of the anchor after the expansion of the blades into the earth and to stop the blades thereagainst from subsequent retraction when strain is applied to the shaft of the earth anchor. Stop 90 means are of course necessary in the operation of directly expanded earth anchors of this type, and I do not claim any particular novelty in this stop means.

In assembling my earth anchor I take my trunnion housing 4 and a set of blades to correspond, and I mount the blades upon their trunnions in the trunnion sockets by passing the blade trunnions up through the hole 14 for the shaft and then sidewise into the trunnion sockets. Then I insert the shaft 1 in the hole 14, whereupon the shaft forms a closure for the open sides of the trunnion sockets and the blades will now be loosely but permanently mounted in the housing. I then slip the bottom plate 2 over the threaded lower end of my shaft, attach the nut 3, and the anchor is complete. The blades are collapsed against the shaft as far as they will go, whereupon, as explained, the elliptical trunnions bind in the sockets and the blades are temporarily held against expansion so that the entire anchor may be conveniently inserted into a hole in the earth. The manner of use of the anchor is well known and need not be described by me.

Various modifications in my device will be within the province of those skilled in the art in adapting it to various conditions. I have already indicated that the number and disposition of the blades may be varied. The blades may be mounted otherwise than upon integrally formed trunnions. A binding pressure so as to hold the blades in collapsed position may be otherwise applied than by means of the elliptical trunnions. For example, the friction may be applied at the ends of the cylindrical trunnions and may be constant throughout the limits of the movements of the blades so that the expansion of the earth anchor may be effected by the tamping 125 130 135 140 145 150 155 160 165 170 175 180 185 190 195 200 205 210 215 220 225 230 235 240 245 250 255 260 265 270 275 280 285 290 295 300 305 310 315 320 325 330 335 tool against frictional resistance all of the way.

Having thus described my invention, what I claim as new and desire to secure by Letters Patent, is:—

1. In an earth anchor a shaft and a bottom plate thereon, a trunnion housing slidably mounted on said shaft, trunnion sockets in said trunnion housing, a plurality of blades each having a trunnion, and said trunnions mounted in said trunnion sockets and held therein by said shaft.

2. In an earth anchor a shaft and a bottom plate thereon, a trunnion housing slidably mounted on said shaft, trunnion sockets in said trunnion housing, a plurality of blades each having a trunnion, said trunnions mounted in said trunnion sockets and held therein by said shaft, and means for holding said trunnions against rotation in said sockets, said means comprising a frictional engagement of said trunnions in said sockets.

3. In an earth anchor a shaft and a bottom plate thereon, a trunnion housing slidably mounted on said shaft, trunnion sockets in said trunnion housing, a plurality of blades each having a trunnion, said trunnions mounted in said trunnion sockets and held therein by said shaft, and means for releasably holding said trunnions against rotation in said sockets, said means comprising a frictional engagement in one position between said trunnions and said sockets, said sockets being wider than they are deep, and said trunnions being of elliptical form.

4. In an earth anchor a trunnion housing comprising a central hole for a shaft, interior trunnion sockets opening to said shaft hole and arranged thereabout, whereby trunnions may be inserted therein, a plurality of blades each having an earth engaging portion, a neck and a trunnion, neck openings in said trunnion housing connecting with said sockets to accommodate said necks during a swinging of said blades, said trunnions being mounted in said trunnion sockets and held therein by a shaft passing through said hole.

5. In an earth anchor a trunnion housing comprising a central hole for a shaft, interior trunnion sockets opening to said shaft hole and arranged thereabout, whereby trunnions may be inserted therein through said shaft hole, a plurality of blades each having an earth engaging portion, a neck and a trunnion, openings in said trunnion housing connecting with said sockets to accommodate said necks during a swinging of said blades, said trunnions being mounted in said trunnion sockets and held therein by a shaft passing through said hole, and frictional means for binding said trunnions in said trunnion sockets.

6. In an earth anchor a trunnion housing comprising a central hole for a shaft, interior trunnion sockets opening to said shaft

hole and arranged thereabout, whereby trunnions may be inserted therein, a plurality of blades each having an earth engaging portion, a neck and a trunnion, openings in said trunnion housing connecting with said sockets to accommodate said necks during a swinging of said blades, said trunnions being mounted in said trunnion sockets and held therein by a shaft passing through said hole, said trunnions being elliptical in cross section, the longer aixs of said elliptical cross section coinciding with the major axis of said blades and being of such length as to cause said trunnions to bind in said sockets when said blades extend at right angles to said housing, said trunnion sockets being shaped to release said trunnions when said blades have been substantially moved out of said right angular position.

7. In an earth anchor a shaft and a bottom plate, a housing slidably mounted on said shaft, trunnion sockets in said housing communicating with a hole to accommodate said shaft, a plurality of blades each having a trunnion, said trunnions mounted in said trunnion sockets and held therein by means of said shaft, whereby when a tamping tool is applied to said trunnion said blades may be caused to swing outwardly from a substantially vertical to a substantially horizontal position, thereby entering the earth, and means on said blades to stop said blades against said bottom plate from retraction.

8. In an earth anchor a shaft and a bottom plate, a housing slidably mounted on said shaft, trunnion sockets in said housing communicating with a hole to accommodate said shaft, a plurality of blades each having a trunnion, said trunnions mounted in said trunnion sockets and held therein by means of said shaft, whereby when a tamping tool is applied to said trunnion said blades may be caused to swing outwardly from a substantially vertical to a substantially horizontal position, thereby entering the earth, and means on said blades to stop said blades against said bottom plate from retraction, and means for releasably holding said blades in vertical or unexpanded position.
